CLAIM

The ornamental design for a battery pack for electronic bar code reader, as shown and described.

DESCRIPTION

FIG. 1 is a front perspective view of a battery pack for electronic bar code reader showing our new design; FIG. 2 is a top plan view thereof;

FIG. 3 is a right side elevational view thereof, the left side elevational view being a mirror image;

FIG. 4 is a front elevational view thereof;

FIG. 5 is a rear elevational view thereof;

FIG. 6 is a bottom plan view thereof.

The left side elevational view of the design is identical with the right side elevational view (FIG. 3).

FIG. 1.

FIG. 2.

FIG. 3.

FIG. 4.

FIG. 5.

FIG. 6.
